UNITED STATES PATENT OFFICE.

WINNING P. McFADDEN, OF SILVER HILL, WEST VIRGINIA, ASSIGNOR OF
ONE-THIRD TO IRA MILLER AND ONE-THIRD TO FRENZY E. MILLER,
OF SILVER HILL, WEST VIRGINIA.

SAFETY-STIRRUP.

No. 828,237.

Specification of Letters Patent.

Patented Aug. 7, 1906.

Application filed October 7, 1905. Serial No. 281,799.

To all whom it may concern:

Be it known that I, WINNING P. McFADDEN, a citizen of the United States, residing at Silver Hill, in the county of Wetzel and State of West Virginia, have invented new and useful Improvements in Safety-Stirrups, of which the following is a specification.

My invention relates to safety-stirrups; and its primary object is to provide a novel and highly useful device of this character which is readily and quickly detached from its support by the tilting of one foot of the rider in the stirrup should he be thrown from his mount, whereby such accidents as occur from the dismounted rider's inability to extract his foot from the stirrup are obviated.

A further object of the invention is to provide a safety-stirrup which comprises but few parts, which is simple and durable of construction, and which may be manufactured and sold at a comparatively low cost.

With the above and other objects in view the invention consists in the construction, combination, and arrangement of parts hereinafter fully described, claimed, and illustrated in the accompanying drawings, wherein—

Figure 1 is a view in front elevation of the safety-stirrup constructed in accordance with my invention, and Fig. 2 is a central vertical sectional view thereof.

Referring to the drawings by reference-numerals, 1 designates a tubular stirrup-supporting member, the upper end thereof having formed integrally therewith an eye 2, through the medium of which the member 1 is secured to the stirrup-strap. (Not shown.)

3 designates the stirrup, which may be of the usual form and construction and which is secured to the lower end of a stem 4. The lower end of the stem 4 is reduced, as at 5, and provided with an opening 6, through which passes the upper end of the stirrup 3. The stirrup 3 may be secured in the opening 6 to provide rigid connection between the stirrup and stem in any suitable manner. The upper end of the stem 4 is provided with a reduced shank 7, said shank fitting loosely within the tubular member 1. The shank 7 is provided with a locking-recess 8, alining with an opening 9 in the tubular member 1. The inward movement of the shank 7 within the tubular member 1 is

limited by means of the shoulder 10, formed by the reduction of the stem 4, whereby the alining in the recess 8 and opening 9 is rendered easy. Bearing-arms 11 are formed integrally with the stem 4 and project laterally therefrom. A lever 12 is pivotally secured between the bearing-arms 11 by means of a pintle 13, the upper end of said lever extending above the bearing-arms and having its extremity bent to provide a locking portion, said locking portion projecting through the opening 9 into the recess 8, whereby to firmly connect the stirrup to the tubular supporting member 1. The lower portion of the lever 12 extends downwardly and is curved outwardly and inwardly to dispose its lower end beneath the stem 4 and between the sides of the stirrup 3. To this lower end of the lever is integrally secured an arcuate-shaped foot-piece 15, said foot-piece being disposed above the tread-portion of the stirrup 3, whereby an undue tilting of the foot of the rider will engage the same and remove the locking portion 14 of the lever from engagement with the recess 8, thereby permitting the stirrup to become detached from its support. The reduced portion 5 of the stem 4 is provided with a recess formed by an annular flange 16, and arranged upon the lever 12 in alinement with said recess is a stud 17. A spring 18 has one end secured within said recess and its other end engaging the stud 17, said spring serving to normally retain the locking portion 14 of the lever 12 in engagement with the recess 8.

It is apparent from the above description, taken in connection with the accompanying drawings, that should a rider be dismounted the foot remaining in the stirrup would be tilted and caused to engage the foot-piece 15. The engagement of the foot-piece 15 would turn the lever 12 upon its pivot, and thereby remove the locking portion 14 thereof from the recess 8, and thereby permit the stirrup to become detached from its support.

By constructing the lever so that its upper end will form the locking member 14 the use of pins and analogous devices to unite the stirrup to a supporting member is obviated and provides a safer connection and renders the device cheaper of manufacture and sale.

Changes in the form, proportions, and minor details of construction may be made

within the scope of the invention without departing from the spirit or sacrificing any of the advantages thereof.

Having fully described and illustrated my invention, what I claim is—

A device of the character described, comprising a tubular supporting member provided with an opening and adapted to be secured to a stirrup-strap, a stem having its upper end reduced to provide a shank and shoulder and having its lower end reduced and provided with an opening, said lower reduced portion being provided with a recess formed by an annular flange, a stirrup secured to said lower reduced portion through

the medium of said opening, bearing-arms secured to the stem, a lever pivotally secured between said arms, the upper end of said lever being bent to provide a locking member and its lower end being provided with a foot plate and a stud, and a spring having one end mounted within said recess and its other end engaging said stud. 20

In testimony whereof I affix my signature in presence of two witnesses.

WINNING P. McFADDEN.
